DESIGN FOR A DISPLAY CASE OR SIMILAR ARTICLE

Augustine J. Long, Jr., Cincinnati, Ohio, assignor to The A. Nash Company, Cincinnati, Ohio, a corporation of Ohio

Application March 19, 1937, Serial No. 68,277

Term of patent 7 years

To all whom it may concern:

Be it known that I, Augustine J. Long, Jr., a citizen of the United States of America and a resident of Cincinnati, in the county of Hamilton and State of Ohio, have invented a new, original, and ornamental Design for a Display Case or Similar Article, of which the following is a specification, reference being made to the accompanying drawing, forming a part thereof.

The figure is a perspective view of a display case or similar article, showing my new design.

I claim:

The ornamental design for a display case or similar article, substantially as shown.

AUGUSTINE J. LONG, JR.
